UNITED STATES PATENT OFFICE.

JULIUS J. KWIK, OF NORTH CALDWELL, NEW JERSEY, ASSIGNOR TO SIMONS, BRO. & CO., A CORPORATION OF PENNSYLVANIA.

DESIGN FOR A MATCH-BOX.

No. 39,199.

Specification for Design.

Patented March 17, 1908.

Application filed January 7, 1908. Serial No. 409,720. Term of patent 7 years.

To all whom it may concern:

Be it known that I, JULIUS J. KWIK, a citizen of the United States, residing at North Caldwell, in the county of Essex and State of New Jersey, have invented a new, original, and ornamental Design for Match-Boxes, of which the following is a specification, reference being had to the accompanying drawings, forming part thereof.

In the drawings, Figure 1 is a front view, and Fig. 2 is a back view, of a match box, showing my new design.

I claim:

The ornamental design for a match box, as shown.

JULIUS J. KWIK.
